UNITED STATES PATENT OFFICE

157,846

AIRPLANE

Donald W. Douglas and Charles G. Brown, Santa Monica, and Carlos C. Wood, Los Angeles, Calif., assignors to Douglas Aircraft Company, Inc., Santa Monica, Calif.

Application December 17, 1948, Serial No. 150,214

Term of patent 7 years

(Cl. D71—1)

To all whom it may concern:

Be it known that we, Donald W. Douglas, Charles G. Brown, and Carlos C. Wood, citizens of the United States and residents respectively of Sonta Monica, Santa Monica, and Los Angeles, all in the county of Los Angeles, and State of California, have invented a new, original, and ornamental Design for an Airplane, of which the following is a specification, reference being had to the accompanying drawings, forming a part thereof.

Figure 1 is a top perspective view of an airplane in flight showing our new design with the landing gear retracted;

Figure 2 is a side elevational view of the subject airplane depicted in Figure 1 with the landing gear extended;

Figure 3 is a bottom plan view of the airplane depicted in Figures 1 and 2 with the landing gear retracted; and

Figure 4 is a front elevational view of the airplane depicted in Figures 1, 2, and 3 with the landing gear extended.

The characteristic features of our design reside

in the portions shown by means of full lines in the drawing.

We claim:

The ornamental design for an airplane, substantially as shown and described.

DONALD W. DOUGLAS.

CHARLES G. BROWN.

CARLOS C. WOOD.
